[57] CLAIM

The ornamental design for a combined basketball game
goal and return net, as shown and described.

DESCRIPTION

FIG. 1 is a perspective view of a combined basketball
game goal and return net showing my new design;

FIG. 2 is a front elevational view thereof;

FIG. 3 is a top plan view thereof;

FIG. 4 is an elevational view of one side, the other side
being substantially identical thereto.

Fig. 2.

Fig. 1.

Fig. 3.
